UNITED STATES PATENT OFFICE.

RICHARD HERBERT LAPAGE, OF WESTMINSTER, COUNTY OF MIDDLESEX,
ENGLAND.

COMPOUND LOCOMOTIVE-ENGINE.

SPECIFICATION forming part of Letters Patent No. 431,899, dated July 8, 1890.

Application filed February 6, 1889. Serial No. 298,835. (No model.)

To all whom it may concern:

Be it known that I, RICHARD HERBERT LAPAGE, a subject of the Queen of Great Britain and Ireland, residing at Great George Street, 5 Westminster, in the county of Middlesex, England, have invented certain new and useful Improvements in Compound Locomotive-Engines, of which the following is a specification.

In compound locomotive-engines as hitherto constructed there have been one high-pressure and one low-pressure cylinder placed side by side inside or outside the frames and working on one axlē. When it is desired to 10 increase the size of the cylinders, in order to obtain sufficient power to work heavy trains— as, for instance, when it is not desirable to increase the pressure in the boiler but still obtain the necessary cylinder capacity—the cylinders, arranged as described above, become 15 too large in diameter to go between the wheels and the frames, and if they are placed outside the frames the crank-pins have to be made very long, and there is danger of the 20 cylinders themselves fouling the loading-gage, existing platforms, tunnels, and the like. According to the present invention, these defects 25 are obviated by the use of two low-pressure cylinders, of which the combined capacity may be equal to that of a single low-pressure cylinder. By this means the use of a 30 large overhanging low-pressure cylinder is obviated, and when the cylinders are placed between the frames longer crank-journals 35 may be obtained. In one arrangement the two cylinders are placed one above the other, each having its own piston and rod, the two piston-rods being connected together by a cross-head, to which a single connecting-rod 40 is journaled. This rod works onto a crank of the same driving-axle as that on which the rod of the high-pressure cylinder also works. The two low-pressure cylinders are supplied from one steam-chest, the ports being so arranged 45 as to deliver steam from the valve-chest to both cylinders at the same time, the exhaust also taking place in the usual way. If desired, there may be more than one steam-chest; but I prefer to work the low-pressure 50 cylinders with one valve-gear. Valves for

working both the low-pressure cylinders and the high-pressure cylinder may be placed in any position, either above, below, or at the sides of the cylinders. When the low-pressure valve is placed either above or below the 55 cylinders, the steam passes direct through one cylinder to the other by ports which unite the two cylinders. It is obvious that the low-pressure cylinders may be placed in any convenient position to attain this object. 60

Referring to the accompanying two sheets of drawings, Figure 1 is a vertical central section through the two low-pressure cylinders of a compound locomotive arranged according to my invention, so much of the locomotive as is necessary to illustrate the application of my invention thereto being shown in elevation. Fig. 2 is a transverse section through the exhaust-passages of the high and low pressure cylinders and the smoke-box of 70 the locomotive.

1 is a high-pressure cylinder, and 2 2 are two low-pressure cylinders of an outside cylinder compound locomotive-engine. The two low-pressure cylinders are in the example 75 shown arranged one directly above the other and provided with one steam-chest 3 and with one distributing-valve 4, that is operated by a link-motion in the ordinary manner.

The upper of the two cylinders 2 is formed 80 with steam and exhaust ports and passages 5 and 6 of the ordinary form, and communicates with the lower cylinder at each end by connecting ports or passages 7. By this construction the two low-pressure cylinders, which 85 are or may be of equal diameter and length, both receive steam from the steam-chest at the same time, the exhaust from each also taking place simultaneously.

8 is the steam-pipe for conveying high-pressure steam to the high-pressure cylinder 1, and 9 is a connecting-pipe for conveying exhaust-steam from this cylinder to the low-pressure cylinders 2. This connecting-pipe may be fitted with a valve-case 10, containing 90 combined intercepting and starting valves constructed to operate in an automatic manner. The pistons of the two low-pressure cylinders are connected by their rods 11 to one slide-block or cross-head 12, that is guided in 95 100

the ordinary manner and coupled to one end of a connecting-rod 13, the other end of which is coupled to the crank-pin 14 of the driving-shaft in the usual manner.

5 15 is the ordinary exhaust or blast pipe common to both low-pressure cylinders.

What I claim is—

1. In a compound locomotive, the combination of a single high-pressure cylinder and 10 two connected low-pressure cylinders, to both of which steam is admitted simultaneously, and from both of which it is exhausted simultaneously.
2. In a compound locomotive, the combination, with a single high-pressure cylinder, of 15 two connected low-pressure cylinders having a common steam-chest and a connecting-pipe between said high-pressure cylinder and said steam-chest, substantially as herein described.
3. In a compound locomotive, the combination, with a high-pressure cylinder, of two connected low-pressure cylinders having their 20 piston-rods coupled to one connecting-rod, substantially as described.
4. In a compound locomotive, the combination, with a high-pressure cylinder, of two connected low-pressure cylinders having their piston-rods coupled to one slide-block and a connecting-pipe to convey exhaust-steam from 25 said high to said low pressure cylinders, substantially as described.
5. In a compound locomotive, the combination of a high-pressure cylinder, two connected low-pressure cylinders, a single distributing-valve for said low-pressure cylinders, and a connecting-pipe between said high and said low pressure cylinders, substantially 30 as described.
6. In a compound locomotive, two low-pressure cylinders connected together at each end by ports or passages, the steam passing 35 through one cylinder to and from the other, substantially as described.
7. In a compound locomotive, two low-pressure cylinders having their piston-rods coupled to one connecting-rod and both cylinders re- 40

ceiving steam from one valve-chest, substantially as described.

8. In a compound locomotive, two low-pressure cylinders having their piston-rods coupled 50 to one connecting-rod and both cylinders receiving steam from the same distributing-valve, substantially as described.

9. In a compound locomotive, two low-pressure cylinders having their piston-rods coupled 55 to one connecting-rod, both cylinders being connected together at each end by ports and passages, substantially as described.

10. In a compound locomotive, two low-pressure cylinders having their piston-rods 60 coupled to one slide-block, both cylinders receiving steam from one steam-chest, substantially as described.

11. In a compound locomotive, two low-pressure cylinders having their piston-rods 65 coupled to one slide-block, both cylinders receiving steam from the same distributing-valve, substantially as described.

12. In a compound locomotive, two low-pressure cylinders having their piston-rods 70 coupled to one slide-block, the cylinders being connected together at each end by ports or passages, substantially as described.

13. In a compound locomotive, the combination of a single high-pressure cylinder with 75 two low-pressure cylinders situated the one above the other and both driving onto one crank-pin, substantially as described.

14. In a compound locomotive, the combination of two low-pressure cylinders 2, piston-rods 11, slide-block 12, distributing-valve 4, and ports or passages 7, substantially as described. 80

In testimony whereof I have signed my name to this specification in the presence of 85 two subscribing witnesses.

RICHARD HERBERT LAPAGE.
